UNITED STATES PATENT OFFICE

2,143,006

WELT BEATING AND SLASHING MACHINE

John B. Hadaway, Swampscott, Mass., assignor to
 United Shoe Machinery Corporation, Paterson, N. J., a corporation of New Jersey

Application October 22, 1936, Serial No. 107,045

11 Claims. (Cl. 12—67.2)

This invention relates to machines for operating upon boots and shoes and is herein illustrated as embodied in a welt beating machine of the type illustrated in United States Letters Patent No. 1,093,697, granted April 21, 1914, upon an application filed in my name.

Machines of the type referred to have been used extensively in beating out the welts of shoes prior to the operation of attaching the soles thereto. One difficulty which has been experienced in the welt beating operation is that the operator has a tendency to advance the shoe past the beating mechanism too rapidly with the result that the welt is not beaten out to the extent that it should be, particularly around the toe portion of the shoe where, because of the sharp bend which the welt makes at that point the welt may be puckered or otherwise bent out of flattened condition. This has frequently resulted in finished shoes in which the toe portions of the welts thereof are not flat and smooth, or necessitates the repetition of the welt beating operation at the toe portion of the shoe with the consequent loss of time upon the part of the operator. In view of the foregoing, it is an object of the present invention to provide an improved welt beating machine by which the advance of the shoe past the beating instrumentalities is closely controlled and by which a thorough beating out of the welt is insured. To this end and as illustrated I have provided a welt beating machine comprising a work rest, and means for beating out a welt positioned in engagement with the work rest, together with feed jaws movable laterally of the work rest for advancing the work, one of the feed jaws being adapted to enter the welt crease of the shoe to act as a guide during the feeding operations.

Preferably and as shown, the feed jaws are mounted upon a bracket which is oscillatable laterally of the work rest, one of the jaws being fixed relatively to the bracket and the other of the jaws being movable in a heightwise direction to clamp the work. Preferably too, there is provided a presser foot which is operable to clamp the welt to the work support between feed movements of the jaws, thus insuring that the work is advanced in definite feed steps after operation of the beating instrumentalities has been properly performed. As shown, the presser foot is serrated for the purpose of roughing the welt to prepare it for the reception of cement. I have also provided a knife operable at the will of the operator to slash the welt, particularly at the toe portion of the shoe, thereby to enable it to be

beaten out smoothly, there being mechanism operable in response to an initiation of the slashing operation of the knife to render the feed jaws inoperative to feed the work.

These and other features of the invention are disclosed in the accompanying drawings, are set forth in the following detailed specification, and will be pointed out in the claims.

In the drawings,

Fig. 12 is a front view in perspective illustrating operation of the various instrumentalities upon a shoe; and

Fig. 13 is a side view in perspective further illustrating the operating instrumentalities upon a shoe. 35

The invention is illustrated as embodied in a welt beating machine, which as shown in Figs. 1, 2 and 3, 12 and 13, comprises a frame 10 supporting a work rest or guide 12 adapted to enter the welt crease of a shoe 13, a hammer 14 mounted for oscillation relatively to the work rest for beating the inseam 15 and the welt 17 of the shoe, a presser foot 16, and work feeding members 18 and 20 for advancing the shoe past the hammer, there being also a knife 22 for producing slashes 23 in the welt when that is considered to be desirable by the operator. 40

The work rest 12 comprises a plate which has a narrow nose portion 24 adapted to enter the welt crease of a shoe, thereby to hold and guide it in proper operative position relatively to the hammer 14 and the knife 22. The work rest 12 45

50

55

is mounted upon a projection 26 on the frame and is secured thereto by a bolt 28 and nut 30.

The hammer 14 comprises a shank portion 32, Figs. 1 and 6, which is adjustably mounted for heightwise movement in a carrier 34, the shank being prevented from turning in the carrier by means of a key 33. The position of the hammer heightwise of the carrier is adjusted by a nut 38 engaging the shank portion 32 and held in adjusted position by a lock nut 40. The hammer is urged resiliently downward by a spring 39 engaging shoulders 41 and 43. The hammer has a flat striking portion 42, Fig. 3, and the side of the hammer in the direction of advancement of the work having a beveled face 44 to facilitate insertion of the work between the hammer and the work support which, as shown, projects laterally beyond the hammer. The hammer is provided with a vertical slot 46 which intersects the striking face of the hammer and is adapted to receive the presser foot 16, the slot being of sufficient size to provide clearance for movement of the presser foot as well as to permit insertion of the knife 22 when the latter is operated.

To provide for oscillation of the hammer relatively to the work rest 12, I mount the hammer carrier 34 upon a rocking lever 48 which has bifurcated end portions 50 carrying a pin 52 upon which the carrier is positioned. The rocking lever 48 has a depending portion 54 mounted upon a shaft 64 and has at its rearward end a split portion 58 slidably engaging a block 60 carried by an eccentric portion 62 (Fig. 9) of a drive shaft 64, the split end portion being held in engagement with the block by means of bolts 66. Upon rotation of the shaft 64 the lever 48 is rocked, thereby to move the hammer 14 heightwise of the work rest.

It is desirable to give a lateral oscillating movement to the hammer in order to smooth down the inseam as well as to press down the welt and to stretch the welt outwardly of the central portions of a shoe. To this end I have provided means for oscillating the hammer carrier 34 forwardly and rearwardly of the machine by means of a lever 68 which has a bifurcated end portion 70 embracing the eccentric portion 62 of the shaft. The lever 68 is pivotally connected at 72 (Figs. 1 and 9) to a bell-crank lever 74 mounted upon the shaft 56 on the frame and having an arm 73 pivotally connected at 80 to a link 82 making pivotal connection at 84 with the carrier 34. Thus, by means of the rocking lever 48 and the lever 68 the hammer is moved heightwise of the work rest 12 and is simultaneously oscillated about the pivot 52 to which the carrier 34 is secured.

The presser foot 16 is arranged to be oscillated in timed relation to the operation of the hammer and movements of the feed members 18 and 20 so that the work will be clamped between the presser foot and the work rest 12 at such times as the hammer is raised and the feed members are inoperative to grip the work. To this end the presser foot 16 is mounted upon a rocking lever 86 (Figs. 1, 9, 11, 12 and 13), pivoted at 88 on the frame and carrying a stud 90 upon which is positioned a slide block 92 located between the forked ends of a lever 96 mounted upon a shaft 98 carried by a bracket 100. The lever 96 is oscillated by means of a second lever 102 mounted upon the shaft 98 and having a laterally projecting pin 104 positioned in a forked portion 106 of the lever 96. The lever 102 is normally urged rearwardly of the machine by pressure exerted upon the forked

end portion 108 of the lever by a threaded eye bolt 110 (Fig. 4), an end of which is positioned in the fork and secured therein by means of nuts 112 and washers 114, there being a spring 116 connected to the eye bolt 110 and to a second eye bolt 118 secured to the lever 68. The spring 116 acting through the eye bolt 110, lever 102 and lever 96 normally operates to rotate the rocking lever 86 about its pivot 88 in a direction to force the presser foot 16 downwardly toward the work rest 12, thereby to grip the work. Downward movement of the presser foot is limited by means of a stop pin 120 (Fig. 1), mounted upon the bracket 100 and adapted to engage a tail 122 depending from the lever 102.

For raising the presser foot in timed relation to the movements of the hammer 14, I have provided a cam 124 (Fig. 11) carried by the lever 14 and adapted to engage a roll 126 on a bracket 128 which is secured to the lever 102 by a belt 130. This provides a positive means for raising the presser foot 16 in that the cam 124 when moved to the left with the lever 14 (Fig. 1) engages the roll 126 and operates to rotate the levers 102, 96 and 86 in a direction to raise the presser foot.

In order to enable the presser foot readily to hold the work against movement laterally of the foot I have provided the bottom surface of the presser foot with teeth 132 (Fig. 13), which extend transversely of the line of feed of the work and are adapted to penetrate slightly into the material of the welt of a shoe being operated on. Preferably in order to provide for longitudinal adjustment of the presser foot the latter has a shank portion 134 (Figs. 12 and 13), which is adapted to be positioned in a groove 136 in the lever 86 and to be secured thereto by a bolt 138 passing through an elongated slot 140 in the lever.

The feed members 18 and 20 are arranged for oscillation laterally of the work rest 12 in advancing the work. To this end, they are mounted upon a bracket 142 (Figs. 1 and 2), which is arranged for oscillation about a vertical stud 144 secured to an upstanding portion 145 of the frame. The bracket 142 has a depending arm 146 secured thereto by bolts 147. The lower end of the bracket has an inturned portion provided with a groove 148 (Fig. 13), adapted to receive a tongue 150 of a lower work feeding member or jaw 18, the member being held in position of longitudinal adjustment by means of a screw 152. It is to be noted that the upper feed portion of the work feeding member 18 is arranged as indicated at 154 to adapt it to enter the welt crease in feeding a shoe. The work support 12 is provided with a recess 156 to receive the jaw 18 in its feeding movements.

The work feeding member or jaw 20 is carried by a vertical plunger 158 (Fig. 1), slidably mounted in ears 160 forming forward extensions of the bracket 142. The feed member 20 has a laterally extending shank portion 162 secured in a head 164 at the lower end of the plunger 158 and held in position therein by screws 166.

Preferably, the work engaging face of the beating member 20 is provided with serrations 168 to assist the member in clamping the work against the jaw 18 during the work feeding movement. These serrations penetrate the welt during the work feeding movements of the jaws, and operate to roughen the welt to prepare it for the reception of cement. The member 20 is normally forced downwardly toward the work by means of

a spring 170 which surrounds the plunger 158, the upper end of the spring bearing against a washer 172 which operatively engages a lever 174, and the lower end of the spring bearing against a collar 176 on the plunger. The collar 176 is provided with a slotted portion 178 adapted to receive a pin 180 fixed upon the frame for preventing rotational movement of plunger and the member 20. The tension of the spring is adjusted by varying the position of the collar 176 heightwise of the plunger and securing it in position by a screw 182, and lock nut 183.

The mechanism for oscillating the bracket 142 is arranged to be operated in response to rocking movements of the lever 48. Accordingly, the lever 48 is provided with an ear 184 (Figs. 1 and 4) having a bushing 186 on which is located an eccentric pin 188 having mounted thereon a fork 190 carrying trunnions 192 which support a slide 194 having thereon a vertical roll 196 mounted on a pin 198. The roll is arranged to engage a curved cam slot 200 in a bracket 202 secured to a second bracket 204 mounted on the pivot 144. The bracket 204 has depending portions 206 which embrace a tail 208 on the bracket 142, there being set screws 210 extending through the portions 206 for engaging the tail. By adjusting these screws the angular position of the bracket 142 when at rest can be adjusted. The brackets 202 and 204 are secured together by a tongue and groove connection 212 and a screw 214. As the lever 48 is oscillated, the slide 194 is moved in a direction forwardly or rearwardly of the machine with the result that the roll 196 will vary its position in the cam slot 200 swinging the bracket 202 back and forth in a horizontal plane and will produce a corresponding movement of the bracket 142 through the connections including the bracket 204 and the depending portions 206. This results in a transverse movement of the feeding members 18 and 20.

The mechanism for operating the feed member 20 in a heightwise direction will now be described. This mechanism comprises a collar 216 (Fig. 2), secured to the plunger 158 by means of a screw 218 and arranged to be engaged by the forward end of the lever 174 which is operated in time relation to movements of the hammer 14 to raise the plunger positively, the plunger being normally forced downwardly by the spring 170. The lever 174 has a forked end 220 (Figs. 2, 9 and 11), bearing a pivot 222 upon which is mounted a block 224 having an elongated slot 226 through which the plunger 158 passes. This slot is for the purpose of providing clearance during angular movements of the bracket 142 and the plunger in the feeding of the work. The washer 172 is forced into engagement with the under side of the block by the spring 170 and the block itself is arranged to engage the under side of the collar 216 at the proper time to raise the plunger.

The lever 174 is operatively connected to and driven by the lever 74. The connections between these levers comprise a sleeve 228 (Figs. 9, 10 and 11) carried at the upper end of the lever 74, a coupling member 230 engaging a pin 231 carried by a stud 232 extending through an opening 234 through the lever 48 and carried by a lever 236 which is pivotally connected at 238 to a lever 240 which is mounted upon a pivot 242 carried by the frame and upon which also is pivoted the lever 174. The lever 174 has an arm 244 extending rearwardly from the pivot 242 carrying a pin 246 upon which is mounted a latch 248 having a hook 250 at the end thereof which is normally adapted

to engage the pivot pin 238 so that the levers 174 and 240 will oscillate together about the pivot 242. To maintain the latch in engagement with the pin 238 there is provided a split collar 252 (Figs. 2 and 7), upon the outer end of the pivot 246 secured thereto by a bolt 253 and having an arm 254 to which is connected a spring 256, the other end of the spring being secured to a projection 258 on the lever 174. The collar 252 carries a member having laterally projecting arms 260 which embrace the lower portion 262 of the lever arm 244 and constitute stops to limit the extent of oscillation of the latch 248. The lever 240 is provided with a contacting portion 264 (Figs. 9, 10 and 11) and the lever arm 244 has a contacting portion 266 which engage each other when the hook 250 is in engagement with the pin 238. In Fig. 2, the latch 248 is shown with its hooked portion in engagement with the pin 238 in which condition the lever 174 will be oscillated periodically causing the feed member 20 to be raised from the work during angular movements of the bracket 142 when the feed member 18 and 20 are moved toward the work rest 12 prior to a feeding operation.

The knife 22 has a laterally curved leg portion 268 (Figs. 5 and 12) and a shank portion 270 which is mounted in a split holder 272 and secured in position by a bolt 274. The holder is carried at the end of a link 276 slidably mounted in a guideway 278 carried by a bracket 280 (Fig. 2), which is adjustably secured to the frame by bolts 282. The link 276 and knife are oscillated by a lever 284 (Figs. 2 and 8), mounted upon a pivot 286 and having at its upper end a guideway 288 receiving a roll 290 mounted upon the rearward end of the link 276. The lever 284 is arranged to be oscillated by a cam 292 having a cam track 294 in which is positioned a roll 296 on the lever 284. The cam is mounted upon a shaft 298 (Figs. 1 and 8), and is driven by a gear 300 from a worm 302 carried by the drive shaft 64, the drive shaft being driven by a pulley 304. The cam 292 is set in operation at the will of the operator by means of a clutch bolt 306 which is arranged to enter a groove 308 and make contact with a projection 309 in the groove upon operation of a starting cam 310 which is carried by an arm 312 pivoted at 314 and movable downwardly upon depression of a treadle rod 316 against the action of a spring 318 secured to the arm 312 and to a pin 320 mounted upon the frame. The cam will rotate one revolution after the clutch bolt is released unless the operator holds down the treadle rod. During a single revolution of the cam the knife is caused to make five forward movements which result in the cutting of a single slit in the welt of the shoe being operated upon. During these five movements the hammer will strike five blows and at the end of the slashing operation the knife will be withdrawn during a single return movement. If it is desired to make more than one slash in going around the toe of the shoe the operator may hold down the treadle rod.

When it is desired to cause the knife to produce a slash in the welt it is of course undesirable to feed the work. I have, therefore, provided means for releasing the feed mechanism during the operation of the knife. Accordingly, the link 276 is provided with a projection 322 (Figs. 2 and 12), which has a rod 324 pivoted thereto at 326. The rod carries a spring 328 one end of which engages a fixed collar 330, the other end of which yieldably engages a pin 334 on a lever 336 and presses 75

the pin against retaining nuts 332 on the rod. The lever 336 is mounted upon a pivot 338 and carries a latch 340 (Figs. 2, 10 and 11), having a hooked portion 342 adapted to engage the pin 246 of the lever arm 244. When the link 276 moves forwardly to cause operation of the knife the latch 340 is rotated in a direction to be swung over the pin 246, thus to hold the lever 174 in raised position, the feeding mechanism being 10 connected at the time by means of a pin 344 carried by the latch 340 which engages a tail 346 of the latch 248, thereby to rotate it in a counter-clockwise direction, as indicated in Fig. 11, with the result that the lever 236 will oscillate without 15 transmitting any motion to the lever 174. At the end of a rotation of the cam 292 as the link 276 moves rearwardly, the latch 248 is withdrawn and the spring 256 causes the hook 250 again to engage the pin 238 rendering the feed mechanism 20 again effective to oscillate the lever 174.

It is to be noted that the cam track 294 is provided with dwell such that the lever 284 is not oscillated until after the jaws 18 and 20 have caused three feed movements of the work subsequent to operation of the treadle rod 316. Consequently, if the rod is held down by the operator a single slash 23 will be produced in the work, after which the lever 284 will be returned to its original position, the feed control mechanism will be effective to advance the work three steps, and then the slashing operation will be repeated.

In the operation of the machine a shoe is presented, as shown in Figs. 12 and 13, to the work support 12 with the narrow edge portion 24 thereof engaging the welt crease of a shoe 13 in such manner that the welt 17 thereof rests upon the upper face of the work rest, the entrance of the shoe between the work rest and the hammer 14 being facilitated by the laterally projecting portion of the work rest which guides the work beneath the relieved face of the hammer. The hammer 14 is oscillated by the lever 48 resiliently to deliver blows to the inseam 15 and to the welt 17 and to move outwardly of the shoe across the welt to smooth it out. Between successive hammer blows the feed jaw 20 engages the welt beneath the hammer and clamps the welt down upon the feed jaw 18. The bracket 142 which carries the feed jaws is swung about its pivot 144 to advance the shoe past the work rest 12 during such time as the hammer 14 and the presser foot 16 are in elevated position. It is to be noted that by having the feed jaws grip the welt close to the operating point, that is, in or adjacent to the paths of movement of the hammer 14 and the presser foot 16, the shoe can be maintained in engagement with the work support 12 and the jaw 18 by exertion of a comparatively light pressure upon the part of the operator and that the shoe can be turned sharply without releasing it from the control of the feed mechanism. At the end of each feed movement the feed jaw 20 is raised and the jaws are moved back toward the work rest 12, during which time the presser foot 16 is depressed to prevent further advance of the work. This cycle is repeated until the side portions of the shoe are beaten out and the toe portion is approached. When, in the opinion of the operator it is desirable to slash the welt in order that it may lie down more smoothly than would otherwise be the case, operation of the treadle rod 316 initiates an operation of the knife 22 which advances intermittently toward the welt 70 during five revolutions of the main shaft of the

machine, the hammer being operated to press down the welt between each partial advance movement of the knife. During this time the feed jaw 20 is held in raised position above the work by means of the latch 340 which holds the lever 174, which controls the position of the feed jaw, in raised position and the mechanism for oscillating the lever 174 including the latch 250 is disconnected. At the end of the slashing operation the upper end of the lever 284 is moved 10 rearwardly, then the latch 340 is released and the latch 250 again causes the lever 174 to oscillate, thereby causing further feed movements of the work.

Having described my invention, what I claim 15 as new and desire to secure by Letters Patent of the United States is:

1. A welt beating machine comprising a work support having a portion adapted to enter the welt crease of a shoe to be operated upon, a welt beating means for delivering blows to a welt positioned upon the work support, and feed jaws located adjacent to the work support and movable laterally thereof for advancing the shoe past the support between blows of the welt beating 25 means, one of said jaws having a thin portion formed and arranged to enter the welt crease of the shoe for guiding the shoe during the feed movements.

2. A welt beating machine comprising a work 30 support for engaging and supporting the welt of a shoe to be operated upon, means for beating out the welt located upon the support, feed jaws mounted adjacent to the support and movable laterally thereof to feed the shoe, a presser foot, 35 and means for moving the presser foot heightwise of the work support to clamp the welt to the support between successive feed movements of the jaws.

3. A welt beating machine comprising a work 40 support, a hammer mounted for movements heightwise of the support to beat out a welt on a shoe and adjacent with the support, a bracket carried by the frame of the machine and movable angularly of the support, a feed jaw carried by the bracket and fixed relatively thereto, a second feed jaw movable heightwise of the first mentioned jaw for clamping the welt thereto, and means for moving the bracket in a direction to advance the shoe past the work support between 45 operations of the hammer.

4. A welt beating machine comprising a work support, a hammer for delivering blows to the welt of a shoe positioned in engagement with the support, feed jaws mounted adjacent to the support and movable laterally thereof for feeding the shoe past the support, a knife mounted adjacent to the support and normally positioned rearwardly thereof, means for advancing the knife to slash the welt, and means for rendering the feed jaws 60 inoperative to feed the shoe prior to an advance movement of the knife.

5. A welt beating and slashing machine comprising a work support, a hammer mounted for movement heightwise of the support for beating out the welt of a shoe in engagement with the support, feed jaws for gripping the welt and advancing it past the support, a presser foot operable to clamp the welt to the support between 65 feeding operations of the feed jaws, a knife arranged for movement across the face of the support to slash the welt, means for initiating a slashing operation of the knife, and means operating in response to initiation of the slashing 70

operation of the knife to render feeding operations of the jaws inoperative.

6. A welt beating machine comprising a frame, a work support carried by the frame and having a portion thereof formed and arranged to enter the welt crease of a shoe to be operated upon, a hammer mounted for movement heightwise of the support, a bracket pivotally mounted upon the frame, a work feed member secured to the bracket and having a thin portion positioned adjacent to the work support and formed and arranged to enter the welt crease of the shoe, a work feed jaw mounted in the bracket for movement heightwise of the feed member, means for oscillating the hammer to beat the welt of the shoe, and means for causing the feed jaw to clamp the welt against the feed member between successive oscillations of the hammer and for moving the bracket in a direction to advance the shoe past the work support.

7. A welt beating machine comprising a work support having a narrow edge portion for entering the welt crease of a shoe to be operated upon, a feed member normally located adjacent to the support and having a narrow edge portion in alignment with that of the support and formed and arranged to enter the welt crease of the shoe, a hammer movable heightwise of the support, a feed jaw constructed and arranged to engage the welt at a point adjacent to the path of the hammer to clamp the welt to the feed member, and means for moving the feed member and feed jaw laterally of the support to feed the work.

8. A welt beating and slashing machine comprising a work support, a hammer constructed and arranged to deliver blows to the welt of a shoe positioned upon the support, feed jaws for gripping the welt adjacent to the support and for feeding the shoe along the support, a knife for slashing the welt, manually operable means for initiating an operation of the knife, and means operably connected to the manually operable means for rendering the feed jaws inoperative to feed the work during a slashing operation of the knife.

9. A welt beating machine comprising a work support, an oscillating hammer for beating the welt of a shoe positioned upon the support, work feeding means for advancing the shoe along the

support, a knife normally located at one side of the support out of the path of advance of the work, means for moving the knife across the support to slash the welt, and means operating upon initiation of a knife operation to cause a predetermined number of feed operations of the feeding means and then to render the feeding means inoperative to feed the work during a single slashing operation of the knife.

10. A welt beating machine comprising a work support, an oscillating hammer for beating the welt of a shoe positioned upon the support, feed members for advancing the shoe along the support, means normally operative to cause work feeding operations of the feed members between successive oscillations of the hammer, a knife for slashing the welt, manually controlled means for operating the knife, and means operable upon the initiation of a knife operation to ensure the occurrence of a predetermined number of feeding operations before and after a single slashing operation of the knife during which the feed members are rendered inoperative to feed the work.

11. A welt beating machine comprising a work support, a hammer for beating out the welt of a shoe positioned in engagement with the support, feed jaws movable laterally of the support for feeding the shoe past the support, a presser foot adapted to clamp the welt to the support between feeding operations of the jaws, means for moving one of the jaws relatively to the other in gripping the work comprising a plunger carrying the jaw, a spring for normally forcing the jaw in a downward direction to grip the work, and a lever for raising the jaw, means for moving the presser foot toward and from the work between feeding movements of the jaws, a lever operatively connected to the presser foot operating means, a latch carried by the jaw operating lever and arranged normally to engage the last mentioned lever so that the two levers will oscillate together, a knife for slashing the welt and normally held in inoperative position, means for causing a slashing operation of the knife, and means operating upon initiation of operation of the last mentioned means for disconnecting the latch and for holding the plunger in raised position thereby to render the feed jaws inoperative during the slashing operation.

JOHN B. HADAWAY. 50

CERTIFICATE OF CORRECTION.

Patent No. 2,143,006.

January 10, 1939.

JOHN B. HADAWAY.

It is hereby certified that error appears in the printed specification of the above numbered patent requiring correction as follows: Page 2, second column, line 55, for the word "arranged" read narrowed; page 3, second column, line 23, for "member" read members; and that the said Letters Patent should be read with this correction therein that the same may conform to the record of the case in the Patent Office.

Signed and sealed this 4th day of July, A. D. 1939.

(Seal)

Henry Van Arsdale
Acting Commissioner of Patents.
